UNITED STATES PATENT OFFICE.

PHILIP NELSON SCOTT, OF WESTWOOD, NEW JERSEY, ASSIGNOR TO WILLIAM C. HALL,
OF HAWORTH, NEW JERSEY, AND JAMES DE TURCK, OF HACKENSACK, NEW
JERSEY.

DISTRIBUTOR FOR IGNITION SYSTEMS.

1,418,836.

Specification of Letters Patent. Patented June 6, 1922.

Application filed August 29, 1919. Serial No. 320,671.

To all whom it may concern:

Be it known that I, PHILIP NELSON SCOTT, a citizen of the United States, residing at Westwood, in the county of Bergen and 5 State of New Jersey, have invented new and useful Improvements in Distributors for Ignition Systems, of which the following is a specification.

My invention consists in a new and useful 10 improvement in distributors for ignition systems for internal combustion engines and is designed more particularly for that type of distributors which is adapted to be used with a magneto or other form of generator which

15 supplies a low tension current to the ignition system. In cases where the current supplied by the generator is of low tension, it becomes necessary to transform such current by passage through an induction coil

20 to provide a current of high tension for use in the spark plugs, in order to secure the necessary spark for ignition in the engine cylinders. Ignition systems which accomplish this transformation of the cur-

25 rent have been of either one of two types; viz: the one type in which the low tension current generated by the magneto has been conducted directly to a single coil and transformed, and the high tension current has 30 been conducted to the distributor and thence to the spark plugs or the other and well known type in which the low tension cur-

35 rent is distributed by the distributor to the coils and thence to the spark plugs, in which system there must be a separate coil for each plug. In the former type, the distributor has to handle a high tension current and secure 40 its distribution, through the friction brush switches, to the spark plugs, through the operation of the ordinary type of "timer." This

has the necessary disadvantage of liability of "sparking" in the timer, on account of the high tension character of the current passing through the switches. The second and 45 familiar type, as indicated, requires an individual coil for each spark plug, resulting in individual adjustment and consequent variation in the ignition with the familiar difficulty of "tuning" the coils, and all the

50 disadvantage of faulty adjustment.

My improved distributor is designed to obviate the foregoing objections and provide for the most efficient transformation of the low tension current and distribution of the 55 high tension current to the spark plugs. In

my device the low tension current is supplied to the distributor and the operation of the "timer" is effected in the usual way, the low tension current being distributed through the switches. From the distributor, the low 60 tension current is conducted to a single coil and transformed. The high tension current is then distributed through a novel form of rotatable switch, in which the liability to "sparking" is obviated, to the spark plugs. 65 The operation of the switch distributing the high tension current, is synchronized with that of the distributor of the low tension current.

It will thus be observed that my device 70 enables the distributor to feed the low tension current supplied by the magneto, in accordance with the requirements of the ignition system, and through the operation of a single coil, to supply high tension current 75 to the spark plugs. In this way, I have obviated the difficulties of handling a high tension current through the switches of the distributor and the more important difficulty of a plurality of coils. The fact that I secure 80 the proper transformation of the current by the use of a single coil, insures uniform ignition throughout the cylinders of the engine, and results in a material increase in the efficient operation thereof, with 85 the consequent reduction of gas consumption.

My invention is clearly disclosed in the details of construction hereinafter pointed out, but it is to be understood that the device 90 shown in the drawings and described is but a single form of device embodying my invention, and the nature and scope of my invention is set forth in the terms of the claims.

In the drawings:

Figure 1 is a rear face view of a distributor embodying my invention, showing the parts assembled.

Figure 2 is a similar view with a portion 100 of the device removed.

Figure 3 is a section on the line 3-3 of Figure 4.

Figure 4 is a section on the line 4-4 of Figure 1.

The particular embodiment of my invention shown in the drawings consists of a distributor having the shell A, which is of the ordinary form, and adapted to be placed upon the casing of the engine so as to fit 110

over the end of the cam shaft, indicated in the drawings as F. This shell A has an outer wall or face A¹, from the center of which extends the circular housing A², the purpose of which will later appear. The shell A is provided upon its inner edge with a recessed portion A³ which is adapted to fit upon a properly adapted annular shoulder upon the engine casing for the reception of the shell A. Mounted upon the top of the shell A is the socket S of the usual type, for the reception of the control rod for controlling the timing of the distributor.

Fitted within the shell A is an insulated ring B, having a circular face portion B¹ adjacent the face A¹. Located within this face portion B¹ is the conductor plate C, composed of copper or other electrical conducting material, provided with bosses C¹ which extend through the insulated face portion B¹, on its side opposite the face A¹, and thereby form contact plates circularly disposed in the face of the portion B¹, within the shell A. In the form shown in the drawings, there are four of these plates C¹. A radial extension C² from the conductor plate C forms an electrical contact with the binding post C³, which passes through the shell A and is insulated therefrom by the insulated collar C⁴, and carries upon its threaded end the usual nuts C⁵. Located at regular intervals in the inner face of the ring B, are the contact plates D similar in character to the contact plates C¹, and electrically connected in series by the electrical conductor D¹ and the connections D² disposed within the ring B. Four of these contact plates are shown. A binding post D³ is connected with the electric circuit connected with the contact plates D, passing through the shell A and being insulated therefrom by the insulated collar D⁴ and having upon its outer end the usual nuts D⁵. Alternately disposed with regard to the contact plates D is a similar number of contact plates E located in the inner face of the ring B in the same circumferential path around the inner face of the ring B with the series of plates D. From each of these plates E, there extends a binding post E¹, through the ring B and the shell A, insulated from the circuit conductor D¹ in the ring B and from the shell A by an insulated collar E², and carrying upon its end the usual nuts E³.

Upon the end of the cam shaft F, which is surrounded by the shell A there is mounted the insulated brush carrier G, by means of a centrally disposed collar G¹, made of copper or some other electrical conducting material. This collar G¹ is locked upon the shaft F in any ordinary way, as by the reduced portion F¹ of the shaft F carrying a lock washer F² having a feather seated in a slot in the shaft F and the collar G¹ and

locked in place by the nut F³ on the threaded portion F⁴ of the shaft F, which extends within the housing A².

Extending radially from the collar G¹ through the carrier G is the conductor G² 70 with which there is in electrical contact the brush socket G³ within which is disposed the brush G⁴ adapted to be protruded from the socket G³ by the coil spring G⁵ within the socket G³. The disposition of the brush G⁴ 75 is such that it is adapted to extend from the carrier G parallel to the shaft F and thus, when the parts are assembled, at right angles to the face portion B¹. Moreover the brush G⁴ is so disposed that rotation of the shaft 80 F causes the brush G⁴ to travel over a circular path upon the face B¹ in which the contact plates C¹ are located. The brush G⁴ thus serves as a switch between the shaft F and the contact plates C¹.

The brush carrier G has an extension G⁶ which is radially disposed in a direction opposite to that portion of the carrier G which carries the brush G⁴. Disposed at an angle of approximately 45° to this extension G⁶ 90 is another radial extension G⁷. In these extensions G⁶ and G⁷, are located the brush sockets G⁸ and G⁹, respectively, in which are carried the brushes G¹⁰ and G¹¹, respectively. The brushes G¹⁰ and G¹¹ are adapted to be protruded from the sockets G⁸ and G⁹ by the coil springs G¹² and G¹³, respectively. The disposition of the brushes G¹⁰ and G¹¹ is such that they are adapted to extend outwardly from the ends of the extensions G⁶ and G⁷, and, when the parts are assembled, to be disposed radially to the inner face of the ring B, and in slidable contact with same. The brushes G¹⁰ and G¹¹ are so disposed in relation to the inner face 100 of the ring B, that when the shaft F is rotated, they are caused to travel over a circular path on the inner face of the ring B in which the contact plates D and the contact plates E are located. The relative location of the brushes G¹⁰ and G¹¹ to one another is such that when either one is in contact with one of the contact plates D, the other one is in contact with one of the contact plates E. Extending between the brush 110 sockets G⁸ and G⁹ and adapted to electrically connect one with the other is the conductor G¹⁴. The construction above described serves as a brush switch by which contact may be secured between any one of the contact plates D and its adjoining contact plate E, through the medium of the brushes G¹⁰ and G¹¹ and their connecting conductor G¹⁴. This switch, as described, being mounted upon the carrier G which is 120 adapted to be rotated by the cam shaft F, is controlled by the operation of the engine.

From the binding post C³ a wire J makes an electrical contact between the conductor plate C with its contact plates C¹ and an in- 130

duction coil of the usual type, not shown. This coil is in electrical contact with the magneto or other generator. As the brush G⁴ is in electrical contact with the cam-shaft F, through the socket G³, the conductor G² and the collar G¹, the circuit through the coil and magneto is closed when by the action of the cam-shaft F, the brush G⁴ is brought into contact with any of the contact plates C¹. Thus it will be seen that the construction above described constitutes a distributor by which the low tension current from the magneto is properly distributed in accordance with the speed of the engine, the pulsations of current being delivered to a single induction coil, instead of to several coils, as in the ordinary system above referred to.

From the binding post D³, a wire I makes an electrical contact between the electrical circuit in which are the contact plates D, and the high tension current circuit of the induction coil. From each of the binding posts E¹, a wire H makes an electrical contact between the plate E and its individual spark plug in each cylinder of the engine.

As the brushes G¹⁰ and G¹¹ are caused to travel over the contact plates D and E, it will be apparent that contact is established through these brushes and plates, between the coil and individual spark plugs, such contact being properly timed by the movement of the brushes which is controlled by the action of the engine through the cam-shaft F. Thus the pulsations of the low tension current when transformed into high tension current are delivered through the wire I, from the single coil, and are properly distributed by means of the rotating brushes to the individual spark plugs.

Having described my invention, what I claim is:

1. The combination in a spark distributor, of three sets of contact points, the points of the first set being positioned to describe a single orbit, and the points of the second and third sets being positioned to describe a single orbit; means adapted to establish contact between the points of said first set and said means; and means adapted to establish contact between the points of said second and third sets.

2. The combination in a spark distributor for internal combustion engines, of a set of contact points; means adapted to establish contact between said points and the engine; a second set of contact points, insulated from said first set; a third set of contact points, insulated from both said first and second sets, the points of said second and third sets being positioned to describe a single orbit; and means adapted to establish contact between the contact points of the second and third sets.

3. The combination in a spark distributor

for internal combustion engines, of a set of contact points; means adapted to establish contact between said points and the engine; a second set of contact points, insulated from said first set; a third set of contact points, insulated from both said first and second sets, the points of said second and third sets being positioned to describe a single orbit; and means adapted to establish contact between the contact points of the second and third sets, said second contact means adapted to synchronize with said first contact means.

4. The combination in a distributor for the ignition system of internal combustion engines, of a low tension current circuit provided with a plurality of contact points; a rotatable brush adapted to establish contact between said points and the cam-shaft of the engine; a high tension current circuit, provided with a plurality of contact points; a plurality of contact points, each electrically connected with the ignition means in each engine cylinder, said high tension contact points and said ignition contact points being positioned to describe a single orbit, and rotatable brushes adapted to establish contact between said high tension contact points and said ignition contact points.

5. The combination in a distributor for the ignition system of internal combustion engines, of a circular plate adapted to be electrically connected with a source of low tension current, and provided with a plurality of contact points thereon; a rotatable brush adapted to establish electrical contact between the said contact points and the cam-shaft of the engine, and to be rotated in accordance with the speed of the engine; a plurality of contact points electrically connected with a source of high tension current; a plurality of contact points connected with the ignition means in the engine cylinders, said high tension contact points and said ignition contact points being positioned to describe a single orbit and rotatable brushes adapted to establish contact between said high tension contact points and said ignition contact points.

6. The combination in a distributor for the ignition system of internal combustion engines, of a circular plate adapted to be electrically connected with a source of low tension current, and provided with a plurality of contact points thereon; a rotatable brush adapted to establish electrical contact between the said contact points and the cam-shaft of the engine, and to be rotated in accordance with the speed of the engine; a plurality of contact points electrically connected with a source of high tension current; a plurality of contact points connected with the ignition means in the engine cylinders; and rotatable brushes adapted to establish

contact between said high tension contact points and said ignition contact points, and being so positioned as to travel in the same orbit.

- 5 7. The combination in a distributor for the ignition system of internal combustion engines, of a circular plate adapted to be electrically connected with a source of low tension current, and provided with a plurality of contact points thereon; a rotatable brush adapted to establish electrical contact between the said contact points and the cam-shaft of the engine, and to be rotated in accordance with the speed of the engine; a plurality of contact points electrically connected with a source of high tension current; a plurality of contact points connected with the ignition means in the engine cylinders; and rotatable brushes adapted to establish contact between said high tension contact points and said ignition contact points, and being so positioned as to travel in the same orbit, all of said brushes being so related as to establish their respective contacts synchronously.

8. In a spark distributor, the combination of a member having a ring portion and a face portion; and a member provided with three brushes, one of said brushes being adapted to contact said face portion, and the other two brushes being adapted to contact said ring portion.

9. The combination in an electric switch, of three sets of contact points, the points in the first set being positioned to describe a single orbit, and the points in the second and third sets being positioned to describe a single orbit; means adapted to establish intermittently an electric contact between the points in the first set and said means; and means adapted to establish intermittently an electric contact between the points in the second and third sets.

10. The combination in an electric switch, of three sets of contact points, the points in the first set being positioned to describe a single orbit, and the points in the second and third sets being positioned to describe a single orbit; means adapted to establish intermittently an electric contact between the points in the second and third sets, said second means being adapted to operate synchronously with said first means.

11. The combination in an electric switch, of a circular member provided with a plurality of contact points; a second circular member provided with a plurality of contact points arranged in two sets; a rotatable shaft disposed concentrically to both circular members; a contact device carried upon said shaft and adapted to contact with the contact points of the first circular member; a

second contact device carried upon said shaft, insulated from said first contact device, and adapted to contact with all the points of the second circular member; and a third contact device carried upon said shaft, insulated from said first contact device and in contact with said second contact device, and adapted to contact with all the contact points of the second circular member.

12. The combination in an electric switch of a circular housing; an insulated lining consisting of a ring portion and a circular face portion within said ring portion; a set of contact points equidistantly disposed in a circular path on said face portion; a second set of contact points equidistantly disposed on the inner face of said ring portion; a third set of contact points alternately disposed with regard to the contact points of said second set; a rotatable shaft disposed concentrically to said ring portion and said face portion; an arm carried on said shaft; a socket in said arm; an electrical conductor adapted to be carried in said socket; a spring adapted to protrude said conductor from said socket and hold said conductor in sliding contact with the face portion of the lining; a second arm carried on said shaft; a socket in said second arm; an electrical conductor adapted to be carried in said socket; a spring adapted to protrude said conductor from said socket and hold said conductor in sliding contact with the inner face of the ring portion of the lining; a third arm carried on said shaft; a socket in said third arm; an electrical conductor adapted to be carried in said socket; a spring adapted to protrude said conductor from said socket and hold said conductor in sliding contact with the inner face of the ring portion of the lining.

13. The combination in an electric switch of a circular housing; an insulated lining consisting of a ring portion and a circular face portion within said ring portion; a set of contact points equidistantly disposed in a circular path on said face portion, an electrical circuit connecting said points; a second set of contact points equidistantly disposed on the inner face of said ring portion, an electrical circuit connecting said points; a third set of contact points alternately disposed with regard to the contact points of said second set, each point of said third set being insulated from all other points in said third set; each of said sets being insulated from the others; a rotatable shaft disposed concentrically to said ring portion and said face portion; a collar on said shaft; an arm on said collar; a socket in said arm; an electrical conductor adapted to be carried in said socket and in electrical contact with said shaft through said socket and collar; a spring adapted to protrude said conductor from said socket and hold said conductor in sliding contact with the face portion of the

lining and adapted to contact with the contact points disposed on said face portion; a second arm carried on said shaft; a socket in said second arm; an electrical conductor adapted to be carried in said socket; a spring adapted to protrude said conductor from said socket and hold said conductor in slid-
able contact with the inner face of the ring portion of the lining and adapted to contact
10 with the contact points disposed on said inner face; a third arm carried on said shaft; a socket in said third arm; an electrical conductor adapted to be carried in said socket; a spring adapted to protrude said

conductor from said socket and hold said 15 conductor in slidable contact with the inner face of the ring portion of the lining and adapted to contact with the contact points disposed on said inner face; an electrical connection between the electrical conductors 20 in said second and third arms.

In testimony whereof I affix my signature in the presence of two witnesses.

PHILIP NELSON SCOTT.
